(57) **CLAIM**

The ornamental design for a docking station for electronic device, as shown and described.

DESCRIPTION

FIG. 1 is a front perspective view of a docking station for electronic device showing our new design; FIG. 2 is a front view thereof; FIG. 3 is a rear view thereof; FIG. 4 is a left-side view thereof; FIG. 5 is a right-side view thereof; FIG. 6 is a top view thereof; FIG. 7 is a bottom view thereof; FIG. 8 is another front perspective view thereof; and, FIG. 9 is a right-side view thereof in an environment of use. The broken lines in FIG. 9 consisting of the large dashes, showing the electronic device, depict environmental subject matter only and form no part of the claim. The dot-dash broken line in the drawings define the bounds of the claim, which extend to the boundary but does not include the boundary. All other broken lines depict portions of the docking station for electronic device that form no part of the claimed design.
